UNITED STATES PATENT OFFICE.

RUDOLF WINKLER, OF DETROIT, MICHIGAN, ASSIGNOR OF THREE-FIFTHS
TO M. D. W. LOOMIS, OF SAME PLACE.

OIL-BURNER.

SPECIFICATION forming part of Letters Patent No. 460,902, dated October 6, 1891.

Application filed April 13, 1889. Serial No. 307,120. (No model.)

To all whom it may concern:

Be it known that I, RUDOLF WINKLER, a citizen of the United States, residing at Detroit, county of Wayne, State of Michigan, have invented a certain new and useful Improvement in Oil-Burners; and I declare the following to be a full, clear, and exact description of the invention, such as will enable others skilled in the art to which it appertains to make and use the same, reference being had to the accompanying drawings, which form a part of this specification.

My invention relates to a new and useful improvement in an oil-burner; and it consists of the devices and appliances and their combinations, as more fully hereinafter described, and set forth in the claims, and more particularly illustrated in the accompanying drawings, in which—

20 Figure 1 is a horizontal section of a portion of a combustion chamber or furnace. Fig. 2 is a horizontal section of the burner, and Fig. 3 is a vertical section of the burner.

I carry out my invention as follows:

25 A represents the combustion-chamber of a boiler-furnace. B denotes the side walls thereof, and B' the front of the furnace.

30 My improved burner consists, essentially, of an inclosing case C, forming a vaporizing-chamber C', said case terminating at its forward end in a nozzle C², preferably made flaring, so that the mouth of the nozzle will be elongated. The nozzle is also preferably cut away at the sides—as, for instance, at c c'—35 to allow the freer distribution of the vaporized oil and to permit its being discharged broadly into the combustion-chamber.

D represents a steam or blast pipe entering the case C, and preferably extending therein, 40 so as to penetrate the nozzle C², the steam-pipe itself terminating in an expanded or flaring nozzle d. This nozzle is also contracted vertically, as shown in Fig. 3.

E and E' are air-pipes communicating with the interior of the case C, and suitably extended therein, as shown, so as to throw the inflowing air well toward the nozzle of the burner.

45 F is a supply-pipe to feed the oil to the nozzle of the burner, the said supply-pipe entering the top of the nozzle C², as shown, and

preferably terminating in said nozzle with a crescent-shaped discharge-nozzle f, the mouth of which is suitably contracted to govern the discharge of the oil therefrom in a thin crescent-shaped sheet and directly forward of the nozzle of the steam-jet through the pipe D.

55 It is to be particularly observed that the openings in the terminal ends of the oil-pipe and steam-pipe, respectively, are of analogous form and that they are elongated in the same direction, the opening in the oil-pipe being in advance of and slightly above the opening in the steam-pipe. The arrangement is therefore such that the oil will feed from the top, 60 being emitted into the vaporizing-chamber in a thin elongated sheet directly in front of the blast issuing from the pipe D, also in a thin elongated blast under pressure, at substantially right angles to the sheet of oil as it is 65 being emitted from the oil-pipe, whereby the oil is instantly sprayed. This construction and arrangement of the terminals of the oil-pipe and blast-pipe proves to be of great efficiency. The case C acts as a shield to prevent the sprayed oil from striking the bottom 70 of the boiler.

75 The oil-supply pipe I prefer to lead through a superheater of any desired construction, (shown in outline at G,) and having a steam-heating pipe H, leading thereinto.

The operation of the device is as follows: The steam-jet through the pipe D, acting as an injector, creates a draft of air through the pipes E E' toward the nozzle C² of the burner, 80 while at the same time the expanded jet of steam through the nozzle d, immediately in the rear of the crescent-shaped nozzle of the oil-pipe, immediately penetrates the oil as it is discharged through the nozzle f, and the 85 commingled air, oil, and steam is discharged broadcast through the flaring mouth of the nozzle C² in the form of vapor into the combustion-chamber and readily consumed. The oil-pipe may be provided with a regulating-valve f'. An additional valve f² may be provided to regulate the flow of oil through the superheater.

90 The device is obviously simple, not liable to get out of order, easily operated, and very 95 efficient. The elongation of the openings in the terminals of the oil and steam pipes is

in the same direction and should be made on the arc of a circle, so that the steam emitted radially from the one opening will vaporize and spread the oil in radial lines laterally as well as straightforward, the radial or lateral dissemination of the vaporized oil being a matter of much importance, as thereby much better combustion and every way more satisfactory results are attained.

10 I prefer to slightly depress the upper edge of the nozzle C², so as to force the vapor more effectually upon the flame, and more especially to prevent it from striking the boiler and coating it with carbon. By thus constructing the nozzle the vapor in combustion is kept down and away from the boiler, so as to be wholly consumed, leaving the boiler free and clean from any deposit thereupon. So, also, as shown, I prefer to taper the case 15 toward the forward end or nozzle C², in order to more effectually concentrate the air and commingle it more efficiently with the steam and vaporized oil.

What I claim as my invention is—

- 25 1. In an oil-burner, the combination of an oil-pipe F, having a vertically-extended extremity terminating in a narrow elongated opening curved in the arc of a circle in its lower end for the emission of oil therefrom in a vertical thin elongated sheet, and a blast-pipe D, extending at an angle to the oil-pipe and terminating at its forward end in a narrow elongated opening curved in the arc of a circle for the emission of a jet or blast therethrough 30 in a thin elongated sheet to spray the oil emitted from the oil-pipe, said openings being each elongated in the same direction and the opening of the oil-pipe arranged in advance of the opening in the blast-pipe in proximity thereto, substantially as described.
- 35 2. In an oil-burner, the combination, with

a case, of an oil-pipe F, led into the top of said case and terminating in a narrow elongated opening curved in the arc of a circle in its lower end for the emission of oil therefrom 45 in the vertical thin elongated sheet, and a blast-pipe D, extending at an angle to the oil-pipe and terminating in a narrow elongated opening at its forward end for the emission of a jet or blast therethrough in a thin elongated sheet to spray the oil emitted from the oil-pipe, said openings being each elongated in the same direction and the opening of the oil-pipe arranged in advance of the openings in the blast-pipe in proximity thereto, substantially as described. 50

3. In an oil-burner, the combination, with a case forming a vaporizing-chamber and provided with a nozzle cut away at its sides and laterally extended and vertically contracted and curved in the arc of a circle, of an oil-pipe led into the top of said nozzle and terminating in a narrow elongated opening curved in the arc of a circle in its lower end for the emission of oil therefrom in a vertical 60 thin elongated sheet, and a blast-pipe D, extending at an angle to the pipe, terminating in a narrow elongated opening at its forward end for the emission of a jet or blast therethrough in a thin elongated sheet to spray the oil 65 emitted from the oil-pipe, said openings being each elongated in the same direction and the opening of the oil-pipe arranged in advance of the openings in the blast-pipe in proximity thereto, substantially as described. 70

In testimony whereof I sign this specification in the presence of two witnesses.

RUDOLF WINKLER.
